UNITED STATES PATENT OFFICE.

CHARLES R. WHEELER, OF GREENE, NEW YORK.

NECKTIE SUPPORTER.

1,427,139.

Specification of Letters Patent. Patented Aug. 29, 1922.

Application filed March 14, 1921. Serial No. 452,033.

To all whom it may concern:

Be it known that I, CHARLES R. WHEELER, a citizen of the United States, residing at Greene, New York, have invented certain 5 new and useful Improvements in Necktie Supporters, of which the following is a clear, full, and exact description.

This invention relates to supports or holders upon which neckties may be tied and 10 which, in turn, serve to support the necktie in proper relation to the collar with which it is worn.

A general object of the invention is to provide a necktie holder which will effectively 15 support a necktie in proper relation to the collar with which it is worn, particularly a necktie of the four-in-hand type, which can conveniently be placed in proper supporting position in the collar and as conveniently re- 20 moved, which causes the tie to present a slightly appearance and, in fact, to give the impression of a tie of its type tied in the usual manner about the collar, and which moreover permits the ready adjustment of 25 the tie to insure the maximum wear thereof.

A particular object of the invention is to provide a necktie holder upon which a four-in-hand tie may conveniently be so tied that a portion of the band is supported at either 30 side of the tied portion of the tie, whereby these lateral band extensions of the tie may be inserted beneath the wings of a turn-down collar in such manner as to give the impression of a tie worn in the usual manner.

35 Other objects and important features of the invention will appear from the following description and claims when considered in connection with the accompanying drawing, in which—

40 Fig. 1 is a front view showing a tie holder embodying the present invention with a tie supported thereon in the preferred manner, the holder and tie being shown in position in the collar with which the tie is 45 to be worn;

Fig. 2 is a front elevation of a tie holder embodying the present invention;

Fig. 3 is a top plan view of the holder shown in Fig. 2;

50 Fig. 4 shows the first step of placing a tie in position upon a holder such as shown in Fig. 2;

Figs. 5, 6 and 7 show, respectively, the succeeding steps in the tying operation; and

55 Fig. 8 shows a modified way of supporting a tie upon a holder of the type herein shown.

The illustrated tie holder is shown as stamped from sheet metal, but it will be understood that the invention is not restricted to a construction in all respects like that 60 herein shown, and that a structure having the essential features of the invention can be made in other ways than that herein shown and described.

In the illustrated construction, the necktie 65 holder is shown as comprising a horizontally elongated frame die out of sheet metal and stamped into the transverse contour shown in Fig. 3, the body of the frame being curved substantially to the neck curvature of the 70 collar band of the collar with which the necktie holder is to be worn. This frame comprises an upper bar 2, upon which the upper loop of a four-in-hand tie is to be carried, and a lower bar 4 connected with the 75 upper bar at its ends so as to form a horizontally elongated loop 6 of the frame, this lower bar 4 carrying a depending fork-like extension 8 adapted to receive within its crotch 10 the shank of the collar button with 80 the curved prongs 12 of the fork resting behind the head of the collar button. It will be noted that the upper part of the crotch 10 is somewhat wider than the passageway between the prongs 12 of the fork whereby 85 these prongs 12 resist both the placing of the structure upon the shank of the collar button and its removal therefrom.

At its ends the horizontally elongated frame is somewhat enlarged to provide a 90 supporting edge about which the band of the tie may be tied, these ends preferably being provided with upstanding arms 14, so arranged as to provide slots 16 between the arms and the body of the frame structure 95 into which slots the band of the tie may be inserted. In order to support the tied portion of the tie in front of the lower bar 4 and in front of its depending button engaging extension 8 and also to support the 100 tied portion of the tie in front of the laterally extending band a part of the bar 2 upon which the upper loop of the four-in-hand tie is carried is preferably forwardly offset with respect to the body of the frame 105 structure, as shown at 18. This bar is also preferably depressed somewhat to bring the upper loop of the tied portion of the tie into proper relation to the collar button, the forward offsetting of the bar 2 at 18 permitting 110 such depression without interfering with the provision of a sufficient opening in the loop

6 to permit the convenient tying of the tie upon the holder.

From the foregoing description, the use of the necktie holder will readily be understood. As shown in Fig. 4, when the necktie is to be tied a part of the band portion of the tie is inserted in the slots 16 with the band in front of both the upper bar 2 and the lower bar 4 as the holder is to be worn. 10 The two ends of the tie are then brought forward about the arms 14, as shown in Fig. 5, and the tying is effected in the usual manner of tying a four-in-hand tie except that when the upper loop is to be formed 15 the end of the wider portion of the tie is brought up through the opening 6, in front of the lower bar and of its button engaging extension 8 and behind the upper bar 2 and its forwardly offset portion 18, and then 20 down through the loop formed by wrapping one end of the tie about the other in the usual manner, the upper loop thus embracing both the upper bar 2 of the holder, particularly the forwardly offset portion 18 of this 25 bar, and that portion of the band of the tie which lies in front of the upper bar 2. The last step of the tying operation is shown in Fig. 7 and, as above pointed out, the tie completely tied and in position upon its 30 holder and in position in the collar is shown in Fig. 1.

Fig. 8 shows a modified way of using the holder shown in Fig. 2. In this case, the band is not extended between the slots 16 35 and in front of the bars 2 and 4, but the tie is simply looped over the bar 2 and particularly over its forward extension 18, the laterally extending portions of the holder being left uncovered.

40 What I claim as new is:

1. A necktie holder comprising a horizontally elongated frame including longitudinal bars, said frame having at its ends upwardly and outwardly inclined slots open at their 45 upper ends to receive the band of a tie, means carried by one of the longitudinal bars of said frame for supporting said frame upon a collar button, the other bar of said frame being offset somewhat to the front of said 50 aforementioned bar when the frame is supported upon the collar button, whereby the upper loop of a four-in-hand tie may be carried by said forwardly offset bar in front of said first mentioned bar.

55 2. A necktie holder comprising a horizontally elongated frame including longitudinal bars, said frame having at its ends upwardly and outwardly inclined arms between which and the body of said frame the band

of a necktie may be located and about which 60 it may be wrapped in the tying operation, and means carried by one of the longitudinal bars of said frame for supporting said frame upon a collar button.

3. A necktie holder comprising a horizontally elongated frame including longitudinal bars, said frame having at its ends upwardly and outwardly inclined arms between which and correspondingly inclined parts of the body of said frame the 70 band of a necktie may be located and about which it may be wrapped in the tying operation, and means carried by one of the longitudinal bars of said frame for supporting said frame upon a collar button, the other 75 bar of said frame being forwardly offset from said first mentioned bar when said frame is supported upon a collar button.

4. The combination with a four-in-hand necktie, of a support therefor comprising a horizontally elongated frame including longitudinal bars, said frame having at its ends upwardly and outwardly inclined arms between which and the body of the frame the 80 band of the necktie is located, and means carried by one of the longitudinal bars of said frame for supporting said frame upon a collar button, the upper loop of said four-in-hand tie being carried upon the other bar of said frame and in front of said first mentioned bar and embracing both the band of the tie and the bar upon which said loop is carried and the band of said tie being looped about said arms.

5. The combination with a four-in-hand necktie, of a support therefor comprising a horizontally elongated frame including longitudinal bars, said frame having at its ends upwardly and outwardly inclined arms between which and correspondingly inclined parts of the body of the frame the band of the necktie is located, means carried by one of the longitudinal bars of said frame for supporting said frame upon a collar button, the upper loop of said four-in-hand tie being carried upon the other bar of said frame and in front of said first mentioned bar and embracing both the band of the tie and the bar upon which said loop is carried and the band of said tie being looped about said arms, 100 said loop supporting bar being offset forwardly from the rest of said holder and the other parts of said holder being shaped to fit the front of the collar band with which 105 said holder is used.

Signed at Greene, N. Y., this 11th day of March, 1921.

CHARLES R. WHEELER.
